AUTOMOBILE EXTENSIBLE TRUNK

Robert E. Stevenson, Indianapolis, Ind.

Application March 17, 1930. Serial No. 436,344

16 Claims. (Cl. 224—29)

This invention relates to the art of trunks of the type adapted to be mounted on automobiles and the like and particularly to that type of trunks that may be enlarged as may be desired 5 to accommodate a varying amount of luggage or loose articles to be carried.

One of the primary purposes of the invention is to provide a trunk structure that will permit the trunk to be enlarged at will and to have a 10 cover extensible therewith. A primary object also resides in the means provided for supporting the extended portion of the trunk to prevent its sagging down and the binding of the various members while being extended.

Other important objects are to be found in the provision of a cover that may be locked at any 15 of the selected positions; in the simple and readily operated means for securing the extended portion at the selected positions; in the particular swinging cantilever bars provided to follow 20 and support the extended trunk portion; and in the general simplicity and uniqueness of the structure permitting the production of a neat appearing trunk at a relatively low cost of 25 production.

These and other objects will become apparent in the following description of the invention as illustrated in one particular form by the accompanying drawing, in which

30 Fig. 1 is a front perspective view of a trunk embodying my invention with the top partly opened;

Fig. 2 is a fragmentary plan view of the trunk in an extended position taken from beneath the trunk looking up at the bottom;

Fig. 3 is a fragmentary side elevation of the trunk in the contracted position; and

Fig. 4 a detail in vertical section on the line 4—4 in Fig. 2.

40 Like characters of reference indicate like parts throughout the several views in the drawing.

I provide a horizontal base bar 10 here shown as having the holes 11, 12 and 13 therethrough as means of attaching this base to any supporting bracket (not shown), for example, on the rear of an automobile over the rear extension of the frame. From this base 10, extends the rear wall 14 and the end walls 15 and 16. Both the end walls 15 and 16 are formed by turning the 50 top ends around and down inside to carry the bottom 17 horizontally therebetween and at a distance above the base 10.

The walls 15 and 16 thus formed have a space within them to receive the side walls 18 55 and 19 with a sliding fit so that these ends 18 and 19 may be freely pushed within these spaces and withdrawn easily. The ends 18 and 19 must slide uniformly and cannot be rocked vertically by reason of the fact that the under sides rest 60 on the bottom 10 while the upper edges slidingly

pass under the top bends of the walls 15 and 16.

Both the ends 18 and 19 are of double thickness of metal, though not necessarily so, and are here shown as having the inner sides carrying the bottom 20 at an elevation that will just permit it to be passed under the bottom 17 with a close sliding fit. The front 21 interconnects the ends 18 and 19 and the bottom 20. That portion of each of the ends 18 and 19 which projects beyond the bottom 20, is provided with a horizontal slot 22, into which is fitted a square shoulder of the head of a bolt 23 to have the bolt projected into a hole in the ends 15 and 16 outwardly therethrough to secure a washer 24 and thumb nut 25. The outer ends of these bolts 23 are preferably headed so as to prevent the loss of the wing nuts 25 and also to prevent the bolts 23 from slipping back far enough to allow the square shoulder on the head to drop out of the slots.

The two ends 15 and 16 are joined along their rear vertical edges by the back 14 which extends a distance above the ends and has a top section 27 hinged thereto along the upper edge. This top section 27 preferably has the side members 28 and 29 adapted to drop down and lap over the upper edges of the sides 15 and 16 to have the lips 30 project inwardly to rest on the ends 15 and 16 to be supported by the edges. Preferably arms 31 and 32 are hingedly connected to the back 14 and the members 28 and 29 to support and retain the top section 27 in an upper position. These arms are of the usual and well known type which may be broken to permit the lowering of the top.

The top section 27 is substantially the same width as that of the ends 15 and 16 so that when it is in the closed position, the front edge comes substantially to the front edges of the ends 15 and 16. Now to provide a cover for the extensible part of the trunk, I provide a forward top section 33 which is attached to fit over the outer side of section 27 on top and has the side members 34 and 35 to drop downwardly on the sides to slide along on the outer sides of the members 28 and 29. The lower ends of these members 34 and 35 are bent around inwardly to engage around the lower edges of the members 28 and 29 so as to telescopically unite this forward section 33 by the members 34 and 35 to the top section 27. Suitable locks 36 are carried on the front 21 to have hasps 37 engage lugs 38 on the front apron 39 extending across between the members 34 and 35 integrally with the top section 33.

Referring now to Fig. 2, I pivotally secure two tubular members 40 and 41 by their ends near the center line of the trunk between the legs of a channel bar 42. The height of these tubular

members 40 and 41 is such that they will slidingly contact the base 10 and be below the bottom 17 a sufficient distance to permit the bottom 20 to slide freely therebetween. The lengths of 5 these tubular members are such that when they are drawn out in the enlargement of the trunk and the outer ends of the members are rocked away from the center line (here approximately in the axis of tube 57) their outer ends will project beyond the forward edge of the base 10. Into the outer ends of these tubular members are telescopically inserted bars 43 and 44 which have their outer ends pivotally attached between the outer ends of the channel bar 45 which is secured along the lower bottom edge of the front 15 21.

Where the trunk is made in relatively large sizes, I provide a screw shaft 55 rotatably fixed by one end to the lower side of the end 21 and 20 screw-threadedly passing through a nut 56 fixed on the end of the tube 57 rigidly held between the base 10 and the bottom 17. On the outer end of the shaft 55 projecting beyond the end 21, I fix a crank 58 as a means of revolving the shaft to carry the end 21 in or out from the sides 15 and 16 as may be desired.

Assuming the trunk to be in a normal contracted position, Fig. 3, the trunk may be used as it there appears, if that particular carrying 30 capacity is desired. The top sections 33 and 27 may be swung open as a unit and closed as a unit and locked by reason of the locks being provided on the front 21. Should the carrying 35 capacity of the trunk in the contracted position not be sufficient, the front 21 may be moved out by turning crank 58 to withdraw the sides 18 and 19 from within the ends 15 and 16 to the desired position which may be maintained by tightening up the wing nuts 25. As the front 21 40 is thus moved outwardly, the bars 43 and 44 are extended from the tubular members 40 and 41 accordingly and by reason of a large proportion of the length of the bars 43 and 44 remaining 45 within the tubular member, the cantilever support of the extended portion is obtained by reason of these tubular members 40 and 41 being pivoted at their ends to the relatively fixed trunk member and resting upon and being supported by the base 10 of said trunk member.

Since the members 40 and 41 are pivoted as 50 are the bars 43 and 44 each by their outer ends, it will be seen that as the end 21 is moved outwardly from the base 10, the levers formed by these telescoping members will tend to approach the center line which is midway between the sides of the trunk and, as the end 21 is pushed back, these same links will tend to swing outwardly from the center line while the bars 43 and 44 will telescope into the tubular members 40 and 41. The members 40 and 41 are 55 always supported upon the base 10.

Where no means are available to support and 60 carry the trunk on the automobile, brackets 50 and 51 may be secured to the downturned flanges 52 and 53 at the ends of the base 10 as a means for support from the frame (not shown) of the automobile. Preferably, the base 10 is also provided with the downturned flange 70 54 along the open edge of the base 10 as a stiffening means over which the tubes 40 and 41 may rest.

While I have here shown and described my 75 invention in the one form as now best known to me it is obvious that many structural changes

may be made therefrom without departing from the spirit of the invention, and I therefore do not desire to be limited by that precise form, nor any more than may be required by the following claims.

I claim:

1. In an extensible trunk, a relatively fixed portion comprising a bottom, back and sides, a movable portion comprising a bottom, front, and ends, said sides and ends being adapted to move telescopically one past the other, and extensible supporting cantilevers oblique to each other carried by the fixed portion and attached to the movable portion to support the movable portion in extended positions. 80

2. In an extensible trunk, a relatively fixed portion comprising a bottom, back and sides, a movable portion comprising a bottom, front, and ends, said sides and ends being adapted to move telescopically one past the other, and extensible supporting cantilevers carried by the fixed portion and attached to the movable portion to support the movable portion in extended positions, and a top in two sections having one of the sections fixed to one of said trunk portions, said two top sections being adapted to be telescopically extended one from the other to provide a complete covering over said two portions. 90

3. In an extensible trunk, a relatively fixed portion, a movable portion telescopically fitted to the fixed portion and extensible supporting cantilevers carried by the fixed portion attached to the movable portion to be extended therewith, said cantilevers being oblique to the direction of movement of the extensible bottom member, and a top in two sections having one of the sections fixed to one of said trunk portions, said two top sections being adapted to be extended one from the other to provide 100 a complete covering over said two portions. 110

4. In an extensible trunk, a relatively fixed portion comprising a bottom, back and sides, a movable portion comprising a bottom, front, and ends, said sides and ends being adapted to move telescopically one past the other, and extensible supporting cantilevers carried by the fixed portion and attached to the movable portion to support the movable portion in extended positions, and means retaining the movable portion at selective positions of extension from the fixed portion. 120

5. In an extensible trunk, a relatively fixed portion, a movable portion telescopically fitted to the fixed portion, and extensible supporting cantilevers carried by the fixed portion attached to the movable portion to be extended therewith, and means retaining the movable portion at selected positions of extension from the fixed portion. 130

6. In an extensible trunk, a relatively fixed bottom, an extensible bottom, a pair of extensible bottom supporting cantilevers secured by their inner ends to the fixed bottom and secured by their outer ends to the extensible bottom 140 at a different distance apart for their inner and outer ends, and means associated with the fixed bottom sustaining the supporting members in a horizontal plane. 145

7. In an extensible trunk, a relatively fixed bottom, an extensible bottom, a pair of extensible bottom supporting members secured by their inner ends to the fixed bottom and secured by their outer ends to the extensible bottom, 150

- and means associated with the fixed bottom sustaining the supporting members in a horizontal plane, said supporting members being cantilevers in telescoping sections and the inner ends being pivotally secured adjacent the center line of the fixed bottom and the outer ends pivotally secured to the extensible bottom at points remote from the center line. 80
8. In an extensible trunk, a relatively fixed bottom, a movable bottom telescopically associated with the fixed bottom, a pair of members hingedly secured by their inner ends under said fixed bottom, a base member under said fixed bottom and supporting said pair of members, a pair of bars telescopically carried by said pair of members and having their outer ends fixed to the movable bottom near its outer edge, the inner ends of said pair of members being secured adjacent the longitudinal center line of the two bottoms, the inner members of said bars being supported by the base member to form them into cantilevers and outer ends of the said bars being secured at points along said outer edge remote from that center line. 85
9. In an extensible trunk, a relatively fixed bottom, a movable bottom telescopically associated with the fixed bottom, a pair of members hingedly secured by their inner ends under said fixed bottom, a base member under said fixed bottom and supporting said pair of members, a pair of bars telescopically carried by said pair of members and having their outer ends fixed to the movable bottom near its outer edge, the inner ends of said pair of members being secured adjacent the longitudinal center line of the two bottoms, the inner members of said bars being supported by the base member to form them into cantilevers and outer ends of the said bars being secured at points along said outer edge remote from that center line, each of said bottoms having ends adapted to lap one over the other, a back fixed to the fixed bottom, a front fixed to the movable bottom, and a top in two sections adapted to be extended to conform to the area presented by moving the movable bottom. 100
10. In an extensible trunk, two load carrying trunk ends, one telescoping horizontally with the other, each open from its top side, and a trunk lid in two telescoping sections adapted to be extended and contracted to close the combined opening over said two ends, one of said lid sections being hinged to a trunk end, the end to which the lid is hinged being higher than the other walls of the trunk, means limiting the extension of the ends one from the other comprising a telescoping cantilever supported by one trunk-end and supporting the other trunk-end, and lock means securing one of said lid sections in a closed position, the other of the lid sections being lapped thereunder. 105
11. In an extensible trunk, two load carrying trunk ends, one telescoping horizontally with the other and each open from its top side, and a trunk lid in two telescoping sections adapted to be extended and contracted to close the combined opening over said two ends, one or more telescoping cantilevers supported by one trunk-end and supporting the other trunk-end, a downturned flange on each side of one of said ends, and two-part supporting arms united by break joints adapted to be secured to said flanges. 110
12. In an extensible trunk, a relatively fixed bottom, a movable bottom telescopically associated with the fixed bottom, a pair of members hingedly secured by their inner ends under said fixed bottom, a base member under said fixed bottom and supporting said pair of members, a pair of bars telescopically carried by said pair of members and having their outer ends fixed to the movable bottom near its outer edge, the inner ends of said pair of members being secured adjacent the center line of the two bottoms and resting upon the base members forming cantilevers, the outer ends of the said bars being secured at points along said outer edge remote from that center line, a flange at each side of said bottom, and a bracket removably attached to each flange. 115
13. In an extensible trunk, a relatively fixed portion having a horizontal base member, a movable portion telescopically fitted to the fixed portion, and telescoping supporting cantilevers carried by the fixed portion and resting upon the base member thereof and attached to the movable portion to be extended therewith, and mechanical means for moving said movable portion. 120
14. In an extensible trunk, a relatively fixed portion, a movable portion telescopically fitted to the fixed portion, extensible supporting members carried by the fixed portion attached to the movable portion to be extended therewith, a top in two sections having one of the sections fixed to one of said trunk portions, said top sections being adapted to be extended one from the other to provide a complete covering over said two portions, and screw means for moving said movable portion and extending said top therewith. 125
15. In an extensible trunk, a relatively fixed bottom having a horizontal base, an extensible bottom, a pair of extensible bottom supporting members secured by their inner ends to the fixed bottom and secured by their outer ends to the extensible bottom, and means associated with the fixed bottom sustaining the supporting members in a horizontal plane, said supporting members being in telescoping sections and the inner ends being pivotally secured adjacent the center line of the fixed bottom at the rear of said bottom and resting upon the base and the outer ends pivotally secured to the extensible bottom at points remote from the center line and screw means for drawing said extensible bottom out and toward said fixed bottom. 130
16. In an extensible trunk, a relatively fixed portion, a movable portion telescopically fitted to the fixed portion, extensible supporting members carried by the fixed portion attached to the movable portion to be extended therewith, and a top in two sections having downturned flanges, one of the sections having an unflanged edge hinged at that edge to one of said trunk portions, the trunk portion to which it is hinged being higher by the width of said flanges than the other trunk portions, said top sections being adapted to be extended telescopically one from the other to provide a complete covering over said two portions at any telescopic adjustment of the latter, said top having edge lips to rest on the trunk edge. 135
17. In an extensible trunk, a relatively fixed portion, a movable portion telescopically fitted to the fixed portion, extensible supporting members carried by the fixed portion attached to the movable portion to be extended therewith, and a top in two sections having downturned flanges, one of the sections having an unflanged edge hinged at that edge to one of said trunk portions, the trunk portion to which it is hinged being higher by the width of said flanges than the other trunk portions, said top sections being adapted to be extended telescopically one from the other to provide a complete covering over said two portions at any telescopic adjustment of the latter, said top having edge lips to rest on the trunk edge. 140
18. In an extensible trunk, a relatively fixed portion, a movable portion telescopically fitted to the fixed portion, extensible supporting members carried by the fixed portion attached to the movable portion to be extended therewith, and a top in two sections having downturned flanges, one of the sections having an unflanged edge hinged at that edge to one of said trunk portions, the trunk portion to which it is hinged being higher by the width of said flanges than the other trunk portions, said top sections being adapted to be extended telescopically one from the other to provide a complete covering over said two portions at any telescopic adjustment of the latter, said top having edge lips to rest on the trunk edge. 145

ROBERT E. STEVENSON.
